US00D903527S

(12) **United States Design Patent** (10) Patent No.: **US D903,527 S**
(45) Date of Patent: ** Dec. 1, 2020

(54) **HOOK SLIDE**

(71) Applicant: **RADIO SYSTEMS CORPORATION**,
Knoxville, TN (US)

(72) Inventor: **Christopher Spater**, Burlington, VT
(US)

(73) Assignee: **RADIO SYSTEMS CORPORATION**,
Knoxville, TN (US)

(**) Term: **15 Years**

(21) Appl. No.: **29/661,782**

(22) Filed: **Aug. 30, 2018**

(51) LOC (12) Cl. **02-07**

(52) U.S. Cl.

USPC **D11/218**
